UNITED STATES PATENT OFFICE.

WILLIAM S. JOHNSON, OF BERWICK, PENNSYLVANIA, ASSIGNOR TO AMERICAN CAR AND FOUNDRY COMPANY, OF ST. LOUIS, MISSOURI, A CORPORATION OF NEW JERSEY.

FORGING-MACHINE.

1,244,741.

Specification of Letters Patent. Patented Oct. 30, 1917.

Application filed September 21, 1915. Serial No. 51,905.

To all whom it may concern:

Be it known that I, WILLIAM S. JOHNSON, residing at Berwick, Columbia county, Pennsylvania, and being a citizen of the United States, have invented certain new and useful Improvements in Forging-Machines, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is an elevation showing my improved machine for forging, certain parts being broken away for added clearness;

Fig. 2 is a horizontal section above that portion of the assembly which is mounted upon the lower table, being principally shown in plan;

Fig. 3 is a horizontal section taken along the same plane but looking upwardly showing the rotatable annulus, the piercers carried thereby, and the other associated parts 30 in inverted plan view;

Fig. 4 is a vertical section through the upper platen, the rotatable annulus carried thereby, the lower die block, and the various parts associated with the enumerated elements, said platen and die block being shown as having been brought together in work-treating relation;

Fig. 5 is a fragmentary sectional view showing a modified form of stripper and 40 stripper collar;

Fig. 6 is a perspective view of the portable bath container; and

Fig. 7 is a perspective view of the stripper illustrated in Fig. 4.

45 The invention relates to new and useful improvements in apparatus for forming steel tubing, preferably closed at one end and open at the opposite end.

In the drawings, the invention is shown 50 as used at the present time in the manufacture of metal articles of relatively short length, though it is to be understood that tubing of greater length may be manufactured by the same apparatus and process.

Referring to the drawings: 1 indicates 55 the stationary press table; 2 the movable press table; 3 a platen which is secured by means of the clamps "4" to the stationary press table; 5 indicates a stationary guide collar which is secured by means of the vertically extending bolts "6" to the platen "3".

Secured by outstanding flanges "7" to the stationary guiding collar "5", is a rotatable piercer carrying annulus "8", which for convenience of rotation, is mounted upon ball 65 bearings "9" interposed between the rotatable annulus and said guiding collar.

At intervals, the rotatable annulus "8" is provided with suitable orifices into which are inserted piercer-carrying members "10" 70 which are screw threaded at their open lower sides and received in the screw threaded portions are removable piercers "11" held in position by the screw threads "12", a number of the piercers "11"—6 in the present instance—being carried by the rotatable annulus before referred to.

The platen "3" is provided with a central hub portion "13" pierced to receive therein the guiding pin "14", the purpose of which 80 will be hereinafter explained.

The piercer carriers "10" are provided at their upper portions with outstanding shoulders 10^a, which fit correspondingly shoul- 85 dered recesses in the rotatable piercer carrying annulus "8"; the members "10" being formed of sufficient diameter to provide a "drive" fit which secures the members "10" in position. Entering the guiding collar "5" at a convenient point with relation to the die 90 hereinafter referred to, is a locking pin "15" held under the influence of the spring "16" normally in engagement with the rotatable piercer carrying annulus, which latter is provided at convenient intervals with re- 95 cesses "16'" corresponding in number with the number of piercers so that the locking pin may enter said recesses, holding the piercers against rotation during vertical movement of the parts of the assembly co-operating therewith.

As shown in the drawings, the guiding pin "14" is in register with the pin seat "16'" formed in the stationary die-block "17".

Said die-block is also provided with a recess "18" of convenient shape and cross section, being circular as shown on the drawing, in which recess is seated the die "19" 105

which die rests upon a hardened tool-steel base "20", said base being perforated for the passage of the stem "21" of the kicking-out pin, which pin is provided with an enlarged head portion "22" adapted to support the metal "23" being operated upon.

In Fig. 4 of the drawings, the parts 19 to 23 before indicated are shown in position with one of the piercers "11" fully inserted in the material 23, and it will be noted that, resting upon the material "23", there is shown a stripper "24" held in position by the stripper collar "25". The object of this stripper is to hold the material operated upon during the extraction of the piercers "11", and the guiding pin "14" is seated in the pin-seat "16" so as to guide the piercers "11" and hold them in proper position so that when the locking pin "15" engages one of the notches "16", piercer "11" will be centered over the bar or section of a billet held in the die "19" to be pierced when said piercer and die 19 are relatively moved together.

25 As the metal "23" has a tendency to expand laterally during the piercing operation and fill the die cavity means must be provided for lifting the metal operated upon after the piercer has performed its 30 function, and this is accomplished by means of the kicking-out pin before referred to cooperating with the stirrup "30" to which are connected a pair of chains "31" and "31'", the upper ends of which chains are connected at suitable times to the hooks "32", while the tables "1" and "2" are near together, and when the table "2" descends, the chains "31" and "31'" will lift the stirrup "30" and as said stirrup "30" bears upon the lower end 40 of the pin "21", the pin with its head "22" will be held stationary during descent of the table "2" thereby lifting the work "23" out of the die "19", it being understood of course that the stripper "24" has been previously 45 withdrawn.

Any suitable means to lock the piercer carrying annulus may be employed, as for example, bar "15a" may be projected through the pendant perforated lugs "16" and into 50 suitable registering openings in the hub portion "13", it being understood that the hub portion is stationary.

As the metal to be operated upon is very hot, means must be provided for cooling the 55 piercers after performing their function, and as water is not suitable for this purpose, a jacketed oil bath is provided as shown in the drawings, in which "40" indicates an outer-shell between which and the shell "41" there is provided a water-containing space which is fed through the pipe "42". The water overflows at the top 60 through the pipe "43". Between the wall "41" and the wall "45", there is provided an 65 oil bath segmental in form into which one

or all of the piercers which are not in alignment with the die "19" may pass as tables "1" and "2" approach each other.

Supplemental to oil bath "46" which is stationary is a portable receptacle "47" 70 shown in the drawings as provided with an elongated handle "48", the receptacle being of sufficient diameter and length to contain a considerable quantity of oil and permit it to be elevated to inclose practically all of 75 one of the piercers "11". This portable bath "47" is important in that it prolongs the life of the piercers due to the fact that as soon as the last used and hottest piercer is withdrawn from the heated billet, the operator dips the receptacle "47" into the oil bath "46" filling it to the right point and at once raises the portable bath to inclose the hottest of the piercers before indicated thereby 80 tempering said piercers from time to time during the operation of the machine and greatly prolonging the life of the piercers. 85

During the operation of the machine in piercing the metal, the die "19" and its base "20" will become very hot. Likewise, the 90 interior of the die may be more or less coated with scale from the hot metal inserted therein, hence the kicking-out pin with its head "22" is made removable so that a stream of suitable vapor, as for example, steam, may 95 be forced into the interior of the die and clean it out, after which the pin may be dropped into position and the operation resumed.

If the piercers were not promptly cooled 100 and tempered in the oil bath before referred to, they would soon cease to be usable due to the heat of the metal operated upon and while various means have been tried to cool the piercers, the oil baths have been found 105 to be the most effective.

In the manufacture of certain products from steel, of which large quantities are now being produced, it has heretofore been the practice to do the forging and afterward 110 draw out the forged product to form a thinner and longer article, but with the method hereinbefore described in connection with the apparatus illustrated in the accompanying drawings, it has been found that the forging process is sufficient and with the parts 115 properly proportioned, an article possessing maximum tensile strength has been produced due in part to the elimination of the drawing-out process and to the condition of the 120 tools performing the work.

It is obvious that various tools may be employed, modifications of the device herein shown and described within the present invention, as for example, the die-block may 125 be made rotatable while the piercer carrying member may be held in fixed position, but an essential feature of the invention is that the piercers be carried into alignment with the dies, preferably one at a time, perform 130

their work and then be so positioned with relation to the die that they may be tempered in the oil bath while not performing the piercing operation.

5. In place of the specific form of stripper and stripper collar before referred to, which form separate units, said parts may be combined and formed so as to interlock with the die-block "17", in which case they will serve 10 as a centering means for the piercers with relation to the dies and as strippers to strip the finished product from the piercers while the piercers are being withdrawn from the dies, or the dies withdrawn from the 15 piercers, as may be most convenient.

For convenience of operation, it is desirable that the piercers and the piercer carrying means be held stationary with reference to vertical movement, and be rotatable while 20 the die-block and its carried die or dies are held stationary on a vertically movable table or platform forming part of a hydraulic press, which press is shown in the drawing only in so far as is necessary to illustrate the 25 operation of the invention.

What I claim is:

1. In combination in a piercing machine, a die supporting member, a female die therein, a stripper-holder overlapping said female die and locking said die in position in its 30 holder, a fixed platen, a rotatable piercer-holder supported thereby, a plurality of piercers carried by said piercer-holder, and a guide pin entering said die-supporting member.

2. In combination in a device of the character described, a female die and a die-holder, a guide pin adapted to be seated in said die-holder, a piercer-carrying-member 40 rotatable about said guide pin and relatively to said female die and a plurality of piercers carried by said member, each of said piercers being at times adapted to register with said female die.

3. In combination in a forging machine, a die block, a female die therein, a guide pin adapted to be socketed in said die block, a platen supporting said guide pin, a piercer-supporting member rotatable about said guide pin and a plurality of piercers held in said piercer-supporting member, each of which is at times adapted to penetrate material in said female die.

4. In combination in a forging machine, a die block, a die therein, a guiding pin adapted to extend into said die block, a platen supporting said guiding pin, a rotatable piercer-carrying member supported by said platen and rotatable about said pin, and a 60 plurality of piercers, each adapted in turn to penetrate metal held in said die, all carried by said piercer-carrying member.

5. In combination in a piercing machine, a die supporting member, a female die therein, a stripper-holder overlapping said fe-

male die, a rotatable piercer-holder, supporting means therefor, a plurality of piercers carried thereby, and a guide pin held by said supporting means and adapted to enter said die-supporting member.

6. In combination in a device of the character described, an upper platen, a lower platen, a female die and a die-holder held on said lower platen, a guide pin held by said upper platen and adapted to be seated 75 in said die-holder, a piercer-carrying annulus supported by the upper platen and rotatable with relation to said female die, and a plurality of piercers carried by said annulus, each of which is adapted to register with said female die.

7. In combination in a forging machine, an upper supporting member, a die block, a female die therein, a guide pin socketed in said upper supporting member and adapted to enter said die block, a piercer-supporting member rotatable about said guide pin and a plurality of piercers held in said piercer-supporting member, each of which is at times adapted to penetrate material in 90 said female die.

8. In combination in a forging machine, a vertically movable die block, a die therein, a relatively fixed guiding pin extending into said die block, a platen carrying said guiding pin, a rotatable piercer-carrying annulus supported by said platen and a plurality of piercers, each adapted in turn to penetrate metal held in said die, all carried by 95 said piercer-carrying annulus.

9. In combination in a piercing machine, a die-supporting member, a female die therein, a stripper-holder overlapping said female die, a rotatable piercer-holder, a plurality of piercers carried thereby, a pin support, a guide pin supported thereby and adapted to enter said die-supporting member. 105

10. In combination in a device of the character described, an upper and a lower 110 platen, a female die and a die-holder carried by the lower platen, a guide pin carried by the upper platen and adapted to be at times seated in said die-holder, a piercer-carrying annulus carried by the upper 115 platen and rotatable with relation to said female die and a plurality of piercers carried by said annulus, each of which is adapted to register with said female die.

11. In combination in a forging machine, 120 a die block, a female die therein, a guide pin adapted to be socketed in said die block, a piercer-supporting member rotatable about said die pin, a support for said pin and said member, and a plurality of piercers 125 held in said piercer-supporting member, each of which is at times adapted to penetrate material in said female die.

12. In combination in a forging machine, a die block, a die therein, a guiding pin 130

adapted to extend into said die block, a platen supporting said guiding pin, a rotatable piercer-carrying annulus supported by said platen and a plurality of piercers, each adapted to turn to penetrate metal held in said die, all carried by said piercer-carrying annulus.

13. In combination in a forging machine, male dies, a carrier therefor adapted to move the same in a circular path, a die-socket member, a tubular die held thereby opposite a location on the male die circular path, a separate die block positioned so as to substantially close one end of the passage 15 through said tubular die, means of support for said die block, said male dies each being adapted to be moved into and out of alinement with said tubular die and means for moving the dies together when alined.

14. In combination in a forging machine, male dies, a carrier therefor adapted to move the same in a circuit, a die socket member, a tubular die held thereby opposite a given location on the male die circuit, a 20 separate die block adapted to shape an end of the work, a support for said die block, said carrier being adapted to move each male die into and out of alinement with said tubular die, means for moving the dies together when alined and telescoping means 25 for preserving the die-alinement.

15. In combination in a forging machine, a pair of die-holding members, a female die in one member and a plurality of male dies 30 carried by the other member, the latter member being rotatably mounted eccentrically of said female die and adapted to carry said male dies into alinement with said female die, means for forcing said die-holding members together when one of said male dies and the female die are alined, and guiding means for preserving the alinement of said dies.

16. In combination in a forging machine, 35 a die-socket member, a tubular die carried thereby, a plurality of male piercers, a rotatable support therefor, a work-ejecting device and means for so relatively moving said socket member and piercer-support that one 40 of said piercers penetrates work in said tubular die, relative movement of the socket member and piercer-support being also adapted to cause a portion of said ejecting device to travel through said die to drive the 45 work toward an open end thereof.

17. In combination in a forging machine, dies of different types adapted to coöperate to form and pierce work, a member carrying one type of said dies and another member carrying a different type thereof, means 50 by which dies of the opposite types are brought from irrelative positions into alinement with each other, said dies being adapted to be brought into coöperative work-treating relation, one of said die-carrying

members being rotatable when the dies are not in said work-treating relation to carry its dies to and from a bathing position, and means for subjecting the dies so carried to a bath.

18. In combination in a forging machine, 70 a die-socket member, a female die seated therein, a stripper member containing a passageway secured in position to retain said die, a displaceable stripper having an aperture adapted to be alined with said passageway, a piercer-carrier, a piercer, and actuating means adapted to relatively move said socket member and piercer-carrier to cause said piercer to pass through said stripper member and stripper and into work-treating relation with said die, said actuating means also being adapted to effect the withdrawal of said piercer, and said stripper member and stripper being adapted to co-operate to strip work from said piercer during such withdrawal.

19. In combination in a forging machine, 75 a female die positioned to coöperate with a male die, a plurality of male dies, a die-holder therefor comprising a non-rotatable member having a bearing, a male die-carrier rotatable about and unsupported by said bearing, a supporting retainer for said carrier maintained in fixed relation with said member, and means by which said carrier 80 may be rotated to bring each of said male dies into alinement with the coöperative female die position, and means for moving alined dies into work-treating relation.

20. In combination in a forging machine, 85 a female die positioned to coöperate with a male die, a die-holder comprising a main supporting member, annuli one of which is in fixed relation to said member and another of which is rotatable and supported by the first mentioned annulus, a plurality of male dies carried by said rotatable annulus, means by which said rotatable annulus may be revolved to bring each of said male dies into alinement with the coöperative female die position, and means for moving alined dies into work-treating relation.

21. In combination in a forging machine, 90 a female die positioned to coöperate with a male die, a die-holder comprising a main member, annuli one of which is supported by said main member and another of which is rotatably mounted on the first mentioned annulus, removable die-socket members carried by said rotatable annulus, male dies held by said socket members, means by which the last mentioned annulus may be revolved to bring each of said male dies into alinement with the coöperative female die position, and means for moving alined dies into work-treating relation.

22. In combination in a forging machine, 95 a female die positioned to coöperate with a male die, a die-holder comprising a base-like

member, annuli supported therefrom and one from the other, one annulus being rotatable, anti-friction devices between the last mentioned annulus and the annulus which 5 supports it, male dies carried by the rotatable annulus, means by which the rotatable annulus may be revolved to bring each of said male dies into alinement with the co-operative female die position, and means for 10 moving alined dies into work-treating relation.

23. In combination in a forging machine, a female die positioned to coöperate with a male die, a die-holder comprising a base-like 15 member, an annulus secured thereto, a rotatable annulus confined between the same and

said base-like member, die socket members seated in said rotatable annulus and retained in place by the latter and said base-like member and otherwise freely movable, male 20 dies carried by said socket members, means for revolving said rotatable annulus to bring each of said male dies into alinement with the coöoperative female die position, and means for moving alined dies into work- 25 treating relation.

In witness whereof I have hereunto set my hand in the presence of two witnesses.

WILLIAM S. JOHNSON.

Witnesses:

JOHN W. SHEFFER,
K. R. KESTER.

It is hereby certified that in Letters Patent No. 1,244,741, granted October 30, 1917, upon the application of William S. Johnson, of Berwick, Pennsylvania, for an improvement in "Forging-Machines," an error appears in the printed specification requiring correction as follows: Page 3, line 124, claim 11, for the word "die" read *guide*; and that the said Letters Patent should be read with this correction therein that the same may conform to the record of the case in the Patent Office.

Signed and sealed this 29th day of January, A. D., 1918.

[SEAL.]

R. F. WHITEHEAD,

Acting Commissioner of Patents.

Cl. 78—9.
